[57] CLAIM

The ornamental design for a book support stand or similar article, as shown and described.

DESCRIPTION

FIG. 1 is a perspective view of a book support stand or similar article showing my new design;

FIG. 2 is a side elevational view thereof; and

FIG. 3 is a perspective view of a modified form of the book support stand or similar article in which the votive candle holder supports are omitted.

The broken line showing of the book and votive candle holders or cups in FIGS. 1 and 2 are for illustrative purposes only.

Fig. 1

Fig. 3
